CLAIM

The ornamental design for a telephone station set, substantially as shown and described.

DESCRIPTION

FIG. 1 is a front, top and right side isometric view of a telephone station set showing our new design;

FIG. 2 is a top plan view;

FIG. 3 is a front elevational view;

FIG. 4 is a left side elevational view;

FIG. 5 is a right side elevational view;

FIG. 6 is a rear elevational view; and

FIG. 7 is a bottom plan view.

The showing of a cord in abbreviated form in the figures is done for ease of illustration and clarity of set representation.

FIG. I.

FIG. 2.

FIG. 3.

FIG. 4.

FIG. 5.

FIG. 6.

FIG. 7.
